AIRSHIP

William N. Noble, New York, N. Y.

Application October 31, 1934, Serial No. 750,775

7 Claims. (Cl. 244—5)

My invention relates to airships in which the wings and body are lighter than air in combination with aeroplane surfaces which assist in keeping the airship aloft, and which may be set to serve as a parachute to permit descent to the earth at substantially a vertical path of travel.

The objects of my invention are:

To provide an airship which rises and descends vertically.

10 To provide an airship having aeroplane surfaces to permit horizontal travel at a saving in power and an increase of lifting capacity.

To increase the safety of air travel.

To provide an airship which may arise from, 15 as well as descend to, and survive on the surface of the sea.

I accomplish these and other objects by the construction herein set forth and shown in the accompanying drawing forming a part hereof, 20 in which:

20 Fig. 1 is a front elevation showing the side planes in lowered position in broken lines for descent as a parachute.

Fig. 2 is a side elevation showing the front and rear planes in lowered position in broken lines for parachute descent.

Fig. 3 is a plan view of my invention.

Fig. 4 is a plan view of one of the swinging side or wing motors.

30 Fig. 5 is an elevation of one of the wing motors showing the motor for revolving it.

Fig. 6 is a fragmentary view showing one of the vents and valves.

Fig. 7 is a fragmentary view showing one of the elevating and lowering motors and segmental rack.

Similar reference numerals refer to similar parts throughout the several views of the accompanying drawing forming a part hereof.

40 My invention comprises a boat 1 having outward projecting sides 2 the under surfaces 3 of which function as planes when in flight. Said projecting sides also serve as the supports for the wing motors 4. Within the boat, with the exception of the machinery space 5, and fuel space 6, I have constructed the entire interior spaces 7 hermetically tight for receiving and storing gas lighter than air to reduce the weight of the ship to assist the motors 8 and propellers 9 in driving, 45 thereby lifting the ship into the air. The four motors 8 and propellers 9 are located near the four corners of the superstructure 16 and may be operated independently to level off the ship in ascent and also in descent. I have provided buoy- 50 ant gas storage spaces 7 in various parts of my

airship in addition to the space in the boat 1. Said gas spaces may be of fabric or other material used in lighter than air ships of the conventional design. The wing motors 4 and propellers 12 which are rotatably connected thereto are preferably swingingly mounted, permitting said motors and propellers to be revolved to change their direction of thrust from fore to abeam and aft, which makes it possible to move my ship side-wise as well as ahead or astern or at an angle 10 between these extreme directions of travel, affording a means of steering the ship without the use of rudders, as well as affording a means of warping the ship into a landing dock or pier.

The upper surface of deck 14 of said boat 1 is 15 preferably provided with the fuselage 15 having cabin navigation and control facilities, baggage and freight space, and such space as is not used for accommodation is preferably fitted with hermetically tight compartments for the storage of 20 gas lighter than air to add to the buoyancy of the ship.

The superstructure 16 above the fuselage 15 forms the principal compartments for the storage of buoyant gas, and also is provided with a plane 20 undersurface 17 which acts as the wings of an aeroplane in sustaining the ship aloft while in flight. The main motors 18 and propellers 19 in the ends of the fuselage 15 in addition to the wing motors 4 and propellers 12 drive the ship 30 on its course while in horizontal flight.

At each side of the superstructure and hingeably secured thereto, I have provided the side planes 20 and 21 which form a continuation of the under surface 17 when in flight and 35 may be lowered, as may be seen by the broken lines in Fig. 1, to serve as a parachute when co-acting with the front and rear planes 22 and 23 in their lowered position, shown by the broken lines in Fig. 2.

40 When said front and rear planes are in their raised or normal position they form an extension to the undersurface 17 of the superstructure, and at each side of said front and rear planes 22 and 23 I have provided ailerons 45 24 to assist in banking and levelling off the position of the ship while in flight, as well as elevators to gain and decrease altitude.

When the wings 20 and 21 and front and rear planes 22 and 23 are lowered to form 50 a parachute, the edges may be locked together to form a substantially air tight joint at the edges 10 thereof.

At each corner of the superstructure 16 I have provided air vents 11 which may be 55

closed and valved off independently of each other to level the ship off while in descent. The valves 25 are preferably operated by the motors 26 and segmental racks 27 which are secured to and swing the valves 25 as desired. Each motor 26 is provided with a pinion 28 engaging said rack 27. All of the movement of wings, front and rear planes and ailerons, as well as the swinging of the wing propelling motors are operated in like manner. The motors operating these various parts are reversible and may be provided with limit switches when desired.

It is believed that the use of motors, pinions and segmental racks for reciprocating, swinging and revolving various devices is so well known that a detailed description in this specification is not necessary. The structural details and machinery also may be any of those commonly used in air travel, and my invention need not be limited to any particular construction.

The operation of my ship is substantially as follows:

When leaving the surface of the water, the propellers 9 are started, raising the ship to the desired altitude, after which the main propelling motors and propellers 19 and wing motors 4 and the propellers 12 driven thereby are started, advancing the ship in a horizontal or inclined direction. The wing motors are swung at the desired angle to steer the ship on its course.

Raising or lowering the altitude of the ship is accomplished by the aileron 24 or by the propellers 9. If it is desired to lower the ship vertically, the wings 21 and front and rear planes 22 and 23 may be lowered until the edges 10 are joined to form a parachute, the velocity of descent may be reduced by increasing the speed of the propellers 9 which if further increased in speed will cause the ship to rise vertically.

The levelling off of the ship while in descent may be assisted by regulating the flow of air through the vents 11 by means of the valves 25 as well as by the regulation of said propellers 9.

The ship is lightened by the use of gas which is lighter than air, which is stored as stated above in all spaces which are not used for accommodations, machinery, supplies, stores, etc., as all of such spaces and the hollow parts of my ship are constructed hermetically tight with this purpose in view.

I do not wish to be limited to the exact detail of propelling motors and construction herein disclosed, as the construction may vary, as seems most expedient for the service and speed for which my ship is designed, and the appended claims succinctly set forth my invention.

The height of the superstructure 16 and therefore the amount of buoyant gas therein and the amount of gas and thickness of the front and back planes 22 and 23 as well as the thickness of the side planes 20 and 21 may vary to change the lifting power of the gas to suit the speed of my air ship and also the frontal resistance and the consequent speed.

The side planes may also be constructed similar to the front and rear planes to increase the buoyancy and gas space 7, and thus the front view of Figure 1 of the drawing in such case will present a larger frontal area similar to the side view of the superstructure 16 as shown in Figure 2 of the side view of my airship.

I claim:

1. In an airship, a boat having projecting sides forming supporting airplane surfaces, the upper surfaces of said projecting sides forming a deck on a plane with the deck of said boat extending inwardly, a fuselage near the center of said deck joined to said deck and terminating into a point at the forward and aft ends of said deck, and a gas filled superstructure secured to said fuselage having a plane under surface extending 10 beyond said fuselage.

2. In an airship, a boat having projecting sides forming supporting airplane surfaces, the upper surfaces of said projecting sides forming a deck on a plane with the deck of said boat extending 15 inwardly, a fuselage near the center of said deck having concave side walls joined to said deck and terminating into a point at the forward and aft ends of said deck and a hollow superstructure having a substantially flat airplane undersurface and 20 a curved upper surface having a gas space between the under and upper surface, hingeably mounted wings at the side of said superstructure and hingeably mounted front and rear planes having a curved upper surface conforming to the 25 curvature of the upper surface of said superstructure having gas spaces between their upper and under surfaces co-acting with said wings when lowered to form a parachute to reduce the 30 velocity of descent of said airship.

3. In an airship, a boat having projecting sides forming supporting airplane surfaces, the upper surfaces of said projecting sides forming a deck on a plane with the deck of said boat extending inwardly, a fuselage near the center of said 35 deck having concave side walls joined to said deck and terminating into a point at the forward and aft ends of said deck and a hollow superstructure having a substantially flat airplane undersurface and a curved upper surface having a gas space between the under and upper surface, hingeably mounted wings at the side of said superstructure and hingeably mounted front and rear planes having a curved upper surface conforming to the curvature of the upper surface of said 40 superstructure having gas spaces between their upper and under surfaces co-acting with said wings when lowered to form a parachute to reduce the velocity of descent of said airship, said 45 wings and said front and rear planes when raised adapted to co-act with the airplane surface of said superstructure to sustain said airship in flight.

4. In an airship, a boat, a superstructure and a fuselage connected to and between said boat 55 and superstructure, hinged fore and aft plane surfaces and hinged side plane surfaces attached to said superstructure each of said plane surfaces joined at their ends when lowered to form a parachute.

5. In an airship, a boat, a superstructure and a fuselage connected to and between said boat and superstructure, hinged fore and aft plane surfaces and hinged side plane surfaces attached to said superstructure each of said plane surfaces 65 joined at their ends when lowered to form a parachute and separated when raised whereby the fore and aft plane surfaces may be raised or lowered independent of said side plane surfaces.

6. In an airship, a boat, a superstructure and a fuselage connected to and between said boat and superstructure, hinged fore and aft plane surfaces and hinged side plane surfaces attached to said superstructure each of said plane surfaces 75

joined at their ends when lowered to form a parachute and separated when raised to permit independent movement of said side plane surfaces in relation to said fore and aft surfaces.

5 7. In an airship, a boat, a superstructure and a fuselage connected to and between said boat and superstructure, hinged fore and aft plane surfaces and hinged side plane surfaces attached

to said superstructure each of said plane surfaces joined at their ends when lowered to form a parachute and separated when raised to provide independent movement of said plane surfaces in relation to each other and said super- 5 structure.

WILLIAM N. NOBLE.
